UNITED STATES PATENT OFFICE.

ERNEST WILDHABER, OF BROOKLYN, NEW YORK, ASSIGNOR TO NILES-BEMENT-POND COMPANY, OF NEW YORK, N. Y., A CORPORATION OF NEW JERSEY.

HOB.

Application filed June 8, 1922. Serial No. 566,856.

To all whom it may concern:

Be it known that I, ERNEST WILDHABER, a citizen of the Republic of Switzerland, residing at Brooklyn, in the county of Kings 5 and State of New York, have invented certain new and useful Improvements in Hobs, of which the following is a specification.

My invention relates to hobs and particularly to ground hobs for cutting teeth on gear wheels, sprocket wheels, spline shafts 10 and similar articles.

One object of my invention is to provide a hob that shall have only a portion of a number of the teeth ground and that shall 15 finish a piece of work in the same manner as a hob having the side surfaces of all the teeth completely ground.

Another object of my invention is to provide a hob that shall have ground ribbons 20 projecting from a portion of the teeth, the ground ribbons being so spirally arranged as to effect a finishing cut when the hob is operating on a piece of work.

A further object of my invention is to 25 provide a hob of the above indicated character that shall have ribbons of ground surfaces projecting from a number of the teeth, the ground surfaces being relieved and so arranged in the form of a spiral as to finish 30 the work which has been roughly cut by the other portions of the hob.

At the present time, it is customary to completely grind the teeth of a hob which is to accurately form a piece of work, such 35 for example, as a gear wheel. The sides and top of the teeth are accurately ground and relieved if a gear wheel is to be cut with precision. It is necessary to grind a hob by reason of the errors which are introduced 40 in the form thereof during the hardening process. The grinding of a hob in such manner is somewhat expensive and takes considerable time.

In a hob constructed in accordance with 45 my invention only a small number of the teeth are ground. Moreover, only a very narrow ribbon of ground surface is formed on any of the teeth. The finishing operation of a helicoidal hob corresponds to the 50 meshing of a spiral pinion with a gear wheel. As is well known, such pinion and gear wheel mesh in a so-called point contact. The surfaces of the gear teeth engage 55 the teeth on the spiral pinion in only single point contacts. In a like manner each cut-

ting side of each hob tooth comes into contact with the finished surface on a blank in a single point, or in a very short line. Accordingly, there is only one point on the side of each tooth cutting edge which effects 60 a finishing cut. The remaining portions of the cutting edge of each tooth are adapted merely to rough out the work being cut. Moreover, the location of the finishing points vary or change according to the tooth being considered. 65

Inasmuch as only predetermined points on a helical hob effect finishing cuts, it is unnecessary to completely grind any of the hob teeth. Moreover, only a very few of 70 the hob teeth need to be ground at all. Accordingly, it is only necessary to grind and relieve the points on the teeth which effect the finishing cut in order to obtain a hob adapted to finish work with precision. Thus, 75 it is unnecessary to grind more than half the number of teeth on a hob and, moreover, the teeth, which are ground, have only a small portion of their surfaces ground and relieved. 80

In grinding a hob in accordance with the usual practice, it is necessary to grind the top surfaces and the rounded outside corners of the teeth. Such grinding of the top surfaces and the outside corners of the teeth 85 requires three settings of the grinding machine and takes somewhat of time. One setting of a grinding machine is required for grinding the top edges and two settings of the machine are required for grinding 90 the outside corners of the teeth. In forming a hob in accordance with my invention, all such operations are unnecessary.

In order to grind certain points or ribbons of the side surfaces of certain teeth on a hob, it is necessary to have such portions of the side surfaces of the teeth project beyond the remaining portions thereof. The projecting portions are ground and relieved 95 and serve to effect a finishing cut. The remaining portions of the ground teeth and the unground teeth serve to rough out the work preparatory to the finishing cut. 100

It would be a somewhat complicated operation to relieve a hob of the above indicated type in accordance with modern practice. However, such a hob may be relieved efficiently and quickly by the method disclosed in my application Serial No. 566,855, filed June 8, 1922. In the process disclosed 110

in such application, each tooth on the blank has a coordinate tooth on the master hob and the teeth on the master hob relieve the teeth on the hob blank. Each tooth of the 5 master hob relieves only one tooth on the hob blank. Accordingly, it is only necessary to provide a master hob having corresponding teeth. No change is necessary in the relieving operation and such a hob is 10 formed as simply and easily as an ordinary hob.

In the accompanying drawings:

Figure 1 is a diagrammatic view of a worm member meshing with an involute 15 gear wheel.

Fig. 2 is a bottom plan view of the worm member and gear wheel shown in Fig. 1.

Fig. 3 is an end view of the worm member shown in Fig. 1.

20 Fig. 4 is a side elevational view of a hob formed in accordance with my invention.

Fig. 5 is a sectional view of the hob shown in Fig. 4.

Fig. 6 is an end sectional view taken along 25 the line 6—6 of Fig. 4.

Fig. 7 is a partial sectional view of a hob showing the ground surfaces near the end thereof.

Fig. 8 is a diagrammatic view illustrating 30 the grinding of grooves in the master hob.

Figs. 9 and 10 are sectional views illustrating master hobs which are adapted to form hobs other than those adapted to cut true involute teeth.

35 Fig. 11 is a diagrammatic plan view of a master hob in engagement with a blank.

Fig. 12 is an end view of the hob and blank shown in Fig. 11.

Referring to Figs. 1, 2 and 3 of the drawings, a worm 1 is shown meshing with an involute gear wheel 2. The worm 1 is assumed to rotate on an axis X—X and the gear wheel is assumed to rotate on an axis Y—Y. The gear wheel 2 is assumed to have 40 straight involute teeth 3. The worm 1 is assumed to correctly mesh with such teeth and to be inclined with respect to the gear wheel at an angle equal to the lead angle at the pitch circle. It is customary to so position 45 a hob with respect to a blank when cutting involute gear teeth on the blank. Although it is customary to so position a hob with respect to the blank, it is in no way essential that such relation between the hob and blank 50 be obtained in all cases.

The lines of action between the worm and the gear wheel are indicated by the lines BO and B'O. The intersection point O is the contact point between the pitch circle 4 of 55 the gear wheel and the pitch circle 5 of the worm. When a worm meshes with an involute gear wheel, the line of action is a straight line and must pass through the contact point O as above stated.

60 65 The side surfaces of the worm teeth inter-

sect the lines of action, when referred to the worm or hob, in contact points which are arranged in the form of helicoidal spirals. Thus, if all the contact points where the worm engages or touches the tooth surfaces 70 of the involute gear were marked on the sides of the worm teeth, a spiral would be drawn. Such a spiral is indicated by the line 6 in Fig. 3 of the drawings.

Referring to Fig. 3 of the drawings, a base 75 cylinder 7, upon which the involute curves of the worm are based, is indicated by a dot and dash line.

The line of action between an involute gear wheel and an involute worm is tangent not only to the base circle or cylinder of the gear wheel but also to the base circle or cylinder of the worm. In

Fig. 3 of the drawings, the line of action OB'' is a line drawn through the point O

tangent to the base circle 7. It is also a well known fact that the contact point travels uniformly on the line of action when involute gear wheels are in mesh. The point

travels an amount equal to the so-called 80 normal pitch for each revolution of the worm. In the case of involute gear wheels with straight teeth, the so-called normal pitch

is equal to the circular pitch of the gear wheel multiplied by the cosine of the pres-

90 sure angle. Thus, in the case of a 20° pres-

ure angle the normal pitch P_n is equal to the circular pitch multiplied by the cosine

20°.

Referring further to Fig. 3 of the drawings, the path of the contact point between 100 the worm and the gear wheel travels uni-

formly on the line which is tangent to the base cylinder 7 and which rotates at a con-

stant speed on the axis X—X. The line

OB'' which is tangent to the base cylinder 7 105 may be considered any such line. The dis-

distance moved by the contact point along the tangent line to the base cylinder per revolution of the tangent line is in proportion to

the normal pitch P_n in the projection shown 110 in Fig. 3 of the drawings. The projection

of OB'' in such figure is in proportion to the actual length of the correspond-

ing part of the line of action. Thus, it 115 may be stated the linear distance covered

per revolution is equal to the normal pitch P_n multiplied by the cosine of the inclina-

tion angle of the line of action when con-

sidered with respect to a plane perpendicular to the axis X—X or to the plane of Fig. 3 of the

drawings. In the projection shown in Fig. 120 3 of the drawings, the contact spiral is very

close to an Archimedean spiral. As well

known, the Archimedean spiral would corre-

125 spond to a point moved towards the axis Y—Y instead of tangentially toward the base cylinder 7.

The contact spiral on the worm may also be determined experimentally if so desired.

The surfaces of the teeth on the worm may

be covered with a thin layer of any suitable paint or chalk and then meshed and operated with an involute gear wheel. The paint or chalk will be removed from the sides of the worm teeth at the points of engagement between the worm and the gear wheel. By such means a line is obtained on the sides of the involute teeth. Such line will be in the form of a spiral, as indicated in Fig. 3 10 of the drawings.

The experimental determination of the contact spiral is applicable not only to involute gear wheels but also to non-involute gear wheels, sprocket wheels and to spline 15 shafts. Such determination of the worm spiral is also applicable to any position of the worm or hob with respect to the gear wheel or blank. In Fig. 1 of the drawings, the worm is shown inclined with respect to 20 the gear wheel at an angle equal to the lead angle at the pitch circle. As heretofore set forth, the positioning of the members at such angle relative to each other is the usual practice but it is not a necessity. The inclination of the worm or the hob may be chosen at will within certain practical limits. It is possible, if so desired, to set the hob or worm with respect to the blank or 25 gear wheel so that the axes of the two members are perpendicularly disposed. The experimental determination of the spiral line of contact on the worm may be used in any 30 of the above cases.

Referring to Figs. 4, 5 and 6 of the drawings, a hob 10 is shown constructed in accordance with my invention. Teeth 11 are formed on the hob by means of axial flutes. Although axial flutes are shown in the drawings, it is to be understood that inclined or 35 spiral flutes may be utilized if so desired. The hob is assumed to cut involute gear teeth and is provided with ground ribbons of relieved projecting surfaces for effecting a finishing cut on the gear blank. In Fig. 5 of 40 the drawings, the lines of action have been indicated by reference characters BO' and B'O as in Fig. 1 of the drawings. Contact points of ribbons 13, 14 and 15 are shown on one side of the hob teeth and on the line of 45 action B'O. Similarly, contact points 16, 17 and 18 on the other side of the hob teeth are located on the line of action BO. The contact spots or ribbons project slightly from the side surface of the teeth in order that such spots may be conveniently ground without grinding the complete side surfaces of 50 55 the teeth.

Referring to Fig. 6 of the drawings, the spiral arrangement of such spots or ribbons of ground relieved surfaces is illustrated. Preferably such ground surfaces as well as 60 the remaining portions of the teeth are radially relieved but if so desired, axial relief or a combination of axial and radial relief 65 may be provided.

Referring to Fig. 7 of the drawings, a hob 20, which is adapted to cut involute gear teeth, is shown partially in section. The hob is provided with teeth 21 and ground relieved spots or ribbons are formed on a 70 portion of the teeth in a manner similar to that indicated in Figs. 4, 5 and 6 of the drawings. The ground relieved surfaces are spirally arranged as shown in Fig. 6 of the drawings. However, it should be noted the 75 ground relieved ribbons on the hob shown in Fig. 7 are located near one end thereof whereas in the hob shown in Figs. 4, 5 and 6, the ground relieved ribbons are located near the center of the hob.

The hob may be placed symmetrically with respect to the blank being operated on or may be moved longitudinally in either direction so as to have an unsymmetrical position with respect to the blank being 80 operated on. The ribbons of ground surfaces on the hob, which effect the finishing cut, should be centrally placed with respect to the work being operated on. Thus, in 85 hobs shown in Figs. 4, 5 and 6 the teeth on one side of the ground ribbons will rough out the hob teeth whereas the teeth on the other side of the ground ribbons will perform no function on the blank. In order to 90 utilize the complete hob, the ribbons of 95 ground surfaces should be located near one end thereof so that the roughing out of the gear teeth may be effected by all of the teeth having no ground surfaces thereon. In a 100 hob constructed in accordance with my invention, it is desirable to accurately set the hob with respect to the blank in order that the ribbons of ground surfaces may be so positioned as to effect the finishing cut. Referring to Fig. 6 of the drawings, it will 105 be noted the ground ribbons do not extend to the back of the hob teeth. The hob ribbons are so limited in order to obtain a clean end for each ribbon.

Referring to Fig. 8 of the drawings, a 110 master hob 25 is shown which is adapted to form hobs in accordance with my invention when operated by the methods disclosed in my copending application, Serial No. 566,855, above referred to. When operating a master hob in accordance with the methods disclosed in my companion application, it is necessary to form grooves on the master hob which will form raised or 115 projecting ribbons on the hob blanks. The master hob 25 is shown provided with teeth 26 and on certain of the teeth are formed 120 grooves 27 by means of the grinding wheel 28. The grooves 27 are formed along the lines of action BO and B'O as in the hobs 125 heretofore considered.

A master hob of the above indicated type may be very simply formed if an unrelieved hob is used in accordance with the method disclosed in my companion application, Se- 130

rial No. 566,855. If a relieved master hob is provided, a relieving motion must be added to the motions of the grinding wheel and the position of the relief for each tooth must be determined and set separately. Such setting is necessary not only for involute hobbs but also for non-involute hobbs. However, when it is considered the number of hob blanks which may be cut by the master hob, such setting is not considered to effect the efficiency of the relieving of hob blanks in accordance with my methods.

In Fig. 9 of the drawings, a hob 30, which is constructed in accordance with my invention, is adapted to cut or shape spline shafts. It will be noted the lines of action B'O and BO are materially different on such a hob from the lines of action shown in Fig. 5 of the drawings. In Fig. 10 of the drawings, a hob 31 is indicated for cutting modified involute gear teeth. In such hob, it should also be noted that the lines of action BO and B'O are materially changed. The change in the lines of action, of course, changes the positions of the ribbons or spots of ground surfaces.

Referring to Figs. 11 and 12 of the drawings, a master hob 35 is shown operating in engagement with a blank 36. The master hob is provided with teeth 37 which are formed by axial flutes 38. The blank is provided with teeth 39 and with axial flutes 40 similar to the axial flutes 38 on the master hob. A certain number of the teeth on the master hob are provided with ground grooves 41 which are adapted to form projecting surfaces 42 on certain of the teeth 39 on the blank. The blank 36 is assumed to rotate in a counter-clockwise direction as indicated by the arrow a' and the master hob 35 is assumed to rotate in a clockwise direction as indicated by the arrow a. The teeth on the hob and the teeth on the blank are shown facing in opposite directions and accordingly, it is necessary to feed the hob and blank towards each other for forming relief on the blank teeth, as set forth in my companion application, Serial No. 566,855. Sometimes, however, in forming hobbs having ribbons of ground relieved surface on a portion only of the teeth, it is desirable to have the faces of the blank teeth and the faces of the hob teeth face in the same direction in order to obviate the necessity of having the master hob accurately relieved. The arrow E in Fig. 12 indicates the line of action of the cutting point on the master hob. Although the teeth on the master hob and the teeth being formed on the blank mesh somewhat in the manner of gear wheels, it will be noted the master hob is made somewhat larger than the blank. Moreover, although the hob and blank are rotated at the same angular speed, a cutting action is effected by the master hob by

reason of the greater peripheral speed of the hob teeth as compared with the blank teeth. In order to effect a cut across the teeth, suitable means must be provided for angularly advancing the hob with respect to the blank. For a more complete description of the method of forming a hob in accordance with my invention, reference may be had to my companion application, Serial No. 566,855.

It will be understood that such changes and modifications may be made in my invention as fall within the limits of the appended claims.

What I claim is:

1. A hob, comprising a thread having any predetermined lead, teeth formed in the thread by flutes, and projecting ground ribbons on the sides of a portion of the teeth, said ribbons being so spirally arranged on the sides of the teeth as to effect the finishing cut.

2. A hob, comprising a thread having any predetermined lead, teeth formed in the thread by flutes, the surface back of a portion of the cutting edge of a number of the teeth being ground, said ground surfaces on the various teeth being arranged in the form of a spiral and so disposed as to make the finishing cut by the hob.

3. A hob, comprising a thread having teeth formed therein by axial flutes, a portion of the side surfaces of a number of the teeth projecting to form raised cutting surfaces, the raised portions of the teeth being ground, and serving to effect the finishing cut and the other portion of the cutting edge of the teeth serving to effect the roughing cut.

4. A hob, comprising a thread having teeth formed therein by flutes, and ribbons of ground surface formed on the sides of a number of the teeth, said ribbons being so located as to effect the finishing cut by the hob.

5. A hob, comprising a thread having teeth formed therein, and projecting ribbons of relieved ground surface formed on the sides of a number of the teeth, said ribbons of ground surface being so located as to effect the finishing cut.

6. A hob, comprising a thread having any predetermined lead, teeth formed in said thread by means of axial flutes, the teeth comprising a portion of the thread having narrow ribbons projecting from the side surfaces thereof, said projecting ribbons being ground and relieved and so located as to effect the finishing cut.

7. A hob, comprising a thread having any predetermined lead, undercut teeth formed in said thread by means of axial flutes, the teeth comprising a portion of the thread having narrow ribbons projecting from the side surfaces thereof, said projecting rib

- bons being ground and relieved and so located as to effect a finishing cut.
8. A hob, comprising a thread having teeth formed therein, and having narrow 5 ribbons of ground surface back of the cutting edges of the teeth, said ribbons of ground surfaces being in the form of helicoids spirally arranged.
9. A hob, comprising a thread having 10 teeth formed therein, relieved ribbons projecting from the sides of the teeth, said ribbons being spirally arranged with respect to the hob axis and so positioned as to effect the finishing cut.
- 15 10. A hob, comprising a thread having teeth formed therein, the surfaces back of a portion of the cutting edges of the teeth being ground, said portions of the cutting edges being so located as to effect a finishing 20 cut in the same manner as a hob having the sides of the teeth completely ground.
- 25 11. A hob, comprising a thread having teeth formed therein, the teeth having side projecting portions, the portions of the cutting edges formed by said projecting portions serving to effect a finishing cut and the remaining portions of the cutting edges serving to effect a roughing cut.
12. A hob, comprising a thread having teeth formed therein, said teeth having non- 30 radially arranged cutting faces and projecting ribbons of relieved ground surface formed on the sides of a number of the teeth, and said ribbons of ground surface being so located as to effect a finishing cut. 35
13. A hob, comprising a thread having teeth formed therein, the cutting faces of said teeth being non-radially arranged and the surfaces of a portion of the cutting edges of the teeth being ground, said portions of 40 the cutting surface being so located as to effect a finishing cut in the same manner as a hob having the sides of the teeth completely ground.
14. A hob, comprising a thread having 45 undercut teeth formed therein by axial flutes, a portion of the side surfaces of a number of the teeth projecting to form raised cutting surfaces, the raised portions of the teeth being ground and serving to 50 effect finishing cuts and the other portion of the cutting edge of the teeth serving to effect the roughing cut.

In testimony whereof, I hereto affix my signature.

ERNEST WILDHABER.
